US00D800098S

(12) **United States Design Patent** (10) Patent No.: **US D800,098 S**
(45) Date of Patent: **** Oct. 17, 2017**

(54) **RFID ANTENNA**

(71) Applicant: **Graphene Security Limited**,
Manchester (GB)

(72) Inventor: **Chung-Ping Lai**, Zhubei (TW)

(73) Assignee: **Graphene Security Limited**,
Manchester (GB)

(**) Term: **15 Years**

(21) Appl. No.: **29/568,826**

(22) Filed: **Jun. 21, 2016**

(51) LOC (10) Cl. **14-03**

(52) U.S. Cl.

USPC **D14/230**

(58) **Field of Classification Search**

USPC D14/138, 230–238.1, 299, 358; D13/182

CPC H01L 33/48; H01L 33/486; H01L 23/02;

H05K 5/00; H01C 13/10

See application file for complete search history.
